UNITED STATES PATENT OFFICE

121,556

DESIGN FOR A CASEMENT WINDOW VENTILATOR

Joseph C. Bancroft, White Plains, N. Y.

Application November 1, 1939, Serial No. 87,986

Term of patent 3½ years

To all whom it may concern:

Be it known that I, Joseph C. Bancroft, a subject of Great Britain, who has indicated intention of becoming a citizen of the United States and has taken out first papers, residing at White Plains, Westchester County, State of New York, have invented a new, original, and ornamental Design for a Casement Window Ventilator, of which the following is a specification, reference being had to the accompanying drawing, forming part thereof.

In the drawing,

Fig. 1 is a top plan view of a casement window ventilator showing my new design;

Fig. 2 is an inside face view thereof;

Fig. 3 is an outside face view thereof;

Fig. 4 is an end elevational view thereof with the ventilator door in closed position; and

Fig. 5 is a similar view in open position.

I claim:

The ornamental design for a casement window ventilator, substantially as shown.

JOSEPH C. BANCROFT.
